Specification for Design.

Patented Apr. 4, 1916.

Application filed December 20, 1915. Serial No. 67,917. Term of patent 14 years.

To all whom it may concern:

Be it known that I, CHARLES G. DIEDRICH, a citizen of the United States, residing at St. Louis, in the State of Missouri, have invented a new, original, and ornamental Design for a Lamp for an Automobile, of which the following is a specification, reference being had to the accompanying drawing, forming part thereof.

Figure 1 is a front view, and Fig. 2 is a side view of an automobile lamp having a signal arm, embodying the design.

Copies of this patent may be obtained for five cents each, by addressing the "Commissioner of Patents, Washington, D. C."

The lamp may be supported on a bracket such as is shown in dotted lines in the drawings.

I claim as my invention:

The ornamental design for a lamp for an automobile, as shown.

CHARLES G. DIEDRICH.
